(57) **CLAIM**

The ornamental design for a pepper mill, as shown and described.

DESCRIPTION

1. Pepper Mill

1.1 is a top plan view of a pepper mill showing my new design;

1.2 is a top front perspective view thereof;

1.3 is a front elevational view thereof; and

1.4 is a bottom plan view thereof.

The broken lines in Figure 1.4 are included for the purpose of illustrating environment and form no part of the claimed design.
